UNITED STATES PATENT OFFICE.

HELEN WARD BASCOM, OF PASADENA, CALIFORNIA.

KNIFE-CLEANER.

1,252,316.

Specification of Letters Patent. Patented Jan. 1, 1918.

Application filed June 27, 1917. Serial No. 177,400.

To all whom it may concern:

Be it known that I, HELEN WARD BASCOM, a citizen of the United States, residing at Pasadena, in the county of Los Angeles and State of California, have invented new and useful Improvements in Knife-Cleaners, of which the following is a specification.

This invention relates to a polishing and sharpening device.

The principal object of this invention is to provide a simple and inexpensive device by which cutlery may be sharpened and polished, said device being so designed as to permit its parts to be readily replaced and to be easily cleaned.

Other objects will appear hereinafter.

The invention is illustrated, by way of example, in the accompanying drawings in which:

Figure 1 is a view in perspective illustrating the application of the device.

Fig. 2 is a view in transverse section illustrating the formation of the fabric cover and the body member upon which it is mounted.

Fig. 3 is a view in perspective illustrating the handle and body of the device.

Fig. 4 is a view in perspective illustrating the removable fabric cover.

Referring more particularly to the drawings, 10 indicates a handle, preferably of wood which is formed as an extension at the end of the body 11. This body is in the form of a paddle and is flat and rectangular in section. As shown in Fig. 3, a series of perforations 12 are made through the paddle and uniformly distributed thereover. The body portion of this paddle is formed with straight smooth sides over which a tubular fabric cover 14 is placed. This cover is of coarse weave and may be constructed

in the same manner as a circular lamp wick, the weave and fabric being the same.

In operation, the fabric cover is slipped over the paddle and is then dampened. A powdered, gritty material, such as scouring powder is then applied to the surface of the fabric and the device is ready for use. The articles to be polished and sharpened are then rubbed over the surface of the fabric, the gritty material acting to produce the desired results. It will be understood that other metal parts of the cutlery may be polished, as well as the blades of knives. The fabric cover may be washed, and the perforations 12 will facilitate a thorough drying of said fabric, which may be renewed when worn out.

It will thus be seen that the device here shown is simple in its construction, may be inexpensively manufactured and affords effective means for polishing and sharpening culinary articles.

While I have shown the preferred form of my knife cleaner as now known to me, it is evident that various changes in the combination, construction and arrangement of parts may be made by those skilled in the art without departing from the spirit of my invention.

I claim:

A cutlery cleaner comprising a paddle formed with a flat rectangular body portion and a handle; said body portion having a series of ventilating perforations; and a tubular fabric cover adapted to be positioned over the body of the paddle and the perforations to receive a scouring material.

In testimony whereof I have signed my name to this specification.

HELEN WARD BASCOM.
